UNITED STATES PATENT OFFICE.

EDWARD BERNARD JAEGER AND EUGENE H. HELLER, OF CHICAGO, ILLINOIS,
ASSIGNORS TO THE HILL PUMP VALVE COMPANY, OF CHICAGO, ILLINOIS, A
CORPORATION OF ILLINOIS.

AEROPLANE.

1,327,869.

Specification of Letters Patent.

Patented Jan. 13, 1920.

Application filed January 9, 1918. Serial No. 211,093.

To all whom it may concern:

Be it known that we, EDWARD BERNARD JAEGER and EUGENE H. HELLER, citizens of the United States, both residing at Chicago, 5 county of Cook, and State of Illinois, have invented a new and useful Improvement in Aeroplanes, of which the following is a specification.

The invention relates to motor vehicles, 10 such as aeroplanes and more particularly to a heating system provided therefor.

The principle of the invention is predicated on the arrangement of a heating system wherein the various parts of the control 15 gear constitute heating devices.

The various movements of aeroplanes in the vertical and horizontal planes are brought about by altering the angle of incidence of certain surfaces which are hinged 20 and moved in the required direction by lever or wheel controls.

The rudder planes are stretched on frame work and are easily controlled by cables trained over small pulleys or other means 25 and connected with arms rigidly attached to their surfaces and projecting from each side. By moving them so as to oppose a portion of their surface to the wind or air, the pilot is able to guide the machine. This movement is accomplished by levers. Either 30 hand or foot control can be used. The former is generally reserved for warping the surfaces or for operating the ailerons upon which the lateral stability depends and for 35 raising or lowering the machine by means of the elevator. The foot control preferably serves for steering the machine.

The principal object of the invention consists in employing the various controls mentioned and other stationary devices in proximity to the pilot as heating elements to enhance the comfort of the pilot or observer in the aeroplane when moving in high altitudes where low temperature prevails.

45 It is a further object of the invention to provide the control gear in the form of hollow bodies amenable to internal heating.

A further object of the invention consists in employing the spent gases of the combustion engine to serve as a heating medium in raising the temperature of the various heating devices.

50 A further object of the invention consists in conducting the exhaust gases of the com-

bustion engine through a series of such control levers, whereby the manipulation of the levers is accompanied by heating of the pilot's hand.

55 A further object constitutes the provision of heating systems wherein the seats are formed hollow and constitute parts thereof, the exhaust gases being conducted through said seats.

60 It is also an object of the invention to provide a wheel control, the wheel being formed with a hollow rim and several of the spokes serving as conductors to effect ingress and egress of the exhaust gases.

65 Still a further object aims at the provision of levers with a partition arranged internally to form a plurality of compartments for the passage of the exhaust gases.

70 It is also an object of the invention to provide means for regulating the passage of the gases through the controlling devices.

75 A further object of the invention embraces certain features of construction and arrangement which tend to enhance the usefulness of such vehicles and to a great extent facilitate operation of the control system of the aeroplane when flying at high altitudes where a low temperature prevails or when flying in cold weather.

80 To the accomplishment of the foregoing objects and others that will become apparent upon perusal of the specification, the preferred embodiment of the invention, which, however, is merely indicative of the principle, is illustrated in the annexed drawings, in which—

85 Figure 1 is a longitudinal section through an aeroplane to which the invention has been applied,

Fig. 2 is a top plan view of the same,

Fig. 3 is a longitudinal section through an aeroplane provided with a modification 95 of the invention,

Fig. 4 is a detail sectional view of a controlling lever,

Fig. 5 is a top plan view of the lower 100 portion of the lever,

Fig. 6 is a section on line 6—6 of Fig. 5,

Fig. 7 is a horizontal section through a foot lever,

Fig. 8 is a front elevation of the lever 105 shown in Fig. 7,

Fig. 9 is a side elevation of said lever with parts shown in section,

Fig. 10 is a section on line 10—10 of Fig. 7, Fig. 11 is a section on line 11—11 of Fig. 12,

Fig. 12 is a side view of a controlling valve, 5 Fig. 13 is a side view of another controlling valve,

Figs. 14 and 15 are respectively longitudinal and transverse sections of the control wheel employed in the aeroplane.

10 Referring to the several views in the drawings, and particularly to Figs. 1 and 2, the aeroplane comprises a body 1 which is of any convenient or suitable construction and is merely shown conventionally, the same as 15 the wings or planes 2 and 3, arranged respectively above and below the body 1 and secured thereto in any approved or convenient manner. The aeroplane is driven by a 20 propeller 4 arranged at the front of the machine and mounted on the shaft 5 of a combustion motor generally designated by 6. The motor is of the so-called V type, that is, the crank case and the cylinders are arranged to form a V. As indicated in the 25 drawings an eight cylinder motor is employed and the cylinders of one row exhaust into a manifold 7 which has branch connections 8 to the appertaining cylinders. The exhaust manifold 9 provided for the 30 other row of cylinders has branch connections 10 with the cylinders. As indicated in Fig. 1 each manifold exhausts into the air through an elbow 11 which is of a size and form to eliminate back pressure on the motor and thus assures efficient operation of 35 the same. The construction of the motor and the arrangement of the general parts of the aeroplane are of ancillary importance as far as the invention is concerned, and for 40 this reason the brief reference to these parts is considered ample.

The exhaust elbow 11 is formed integral with or if preferred has secured thereto an extension 12 for the reception of the flexible 45 tube 13, whereby a portion of the exhaust gases is delivered to a series of heating units provided in the aeroplane, which will be described in detail hereinafter. The flexible tube 13 is secured to the casing 14 of a 50 control valve and connected to a foot lever generally designated by 15. The exhaust gases pass through the foot lever 15 and are conducted by a flexible tube 16 to the control wheel 17 which is equipped with a cable 55 sheave 18, whereby the surfaces of the planes may be deflected for the purpose of maintaining the balance of the flying machine.

The control wheel 17 has connected to its opposite side a flexible tube 19 whereby the 60 exhaust gases conducted through the control wheel are carried out and as shown the flexible tube is connected to the seat 20 for the pilot. The seat is constructed hollow for the 65 purpose of affording a chamber receiving the exhaust gases whereby the seat of the

pilot is warmed and thus adds to the convenience of the pilot when the flying machine is moving through zones where a low temperature prevails. The seat 20 is provided with an outlet connection 21 adjacent 70 to the upper edge of the back and a pipe 22 establishes communication between the hollow seat 20 and the atmosphere.

The construction of the several elements for the passage of the exhaust gases will be 75 discussed in detail hereinafter. The aeroplane indicated in Fig. 1 is equipped with a double set of controlling levers and other parts for the purpose of enabling the observer usually accompanying the pilot to effect the manipulation of the surfaces of the machine when for any reason whatever the pilot becomes disabled.

To this end the exhaust elbow 23 of the 80 exhaust manifold 9 is also equipped with an extension 24 to which a flexible pipe 25 is secured which leads to the control valve 26 secured to the foot lever 27 with which the valve is in communication. The exhaust gases in this case also pass through the control valve and through predetermined channels in the foot lever 27 and pass out of the 85 same at the rear side thereof and into a flexible pipe 28 secured thereto which leads to a control wheel 29 equipped with a sheave 30. 90 A flexible pipe 31 secured to the front side of the wheel hub connects the latter with a seat 32 of hollow construction and also provided at its upper end with a pipe 33 which establishes communication between the hollow 95 seat and the atmosphere.

From the foregoing it is evident that the 100 exhaust gases of the combustion motor are conducted through a series of controlling elements which have to be manipulated by the pilot or observer and which also act as radiators to distribute the heat imparted thereto by the gases. The temperature prevailing in the body of the flying machine 105 will be raised to a degree to render the presence of the pilot and observer comfortable even in zones where low temperatures prevail.

The control valve generally designated by 110 14 comprises a tubular casing 34 provided at one end with a plurality of lugs 35 spaced around the circumference of the casing 120° apart from each other and provided with 115 openings 36 for the passage of bolts whereby the valve is secured to similar lugs 64 of the foot control lever 15. A spindle 37 transversely arranged with respect to the 120 axis of the casing extends through the same in an oblique direction. The casing 34 is formed with a projecting pocket 38 at one 125 side to receive one end of the spindle and at the diametrically opposed side a tubular extension 39 is formed integral with the 130 casing affording a bearing for the other end of the spindle, which carries a butter-

fly valve 40 rigidly secured thereto whereby the passage through the casing may be controlled in accordance with the position of the valve.

5 The tubular extension 39 is internally threaded for a portion of its length to receive an element 41 in threaded engagement which bears against a packing 43 held in place by a short sleeve 42. At its other end 10 the extension 39 is provided with a circular flange 44 cut away at 45 to limit the oscillatory movement of the valve spindle 37. To the spindle 37 an arm 46 is secured by a washer 47 and a lock nut 48 threaded on 15 the spindle. The arm 46 has a handle 49 at its outer extremity and is formed with a lug 50 at its inner side arranged in registry with the cut away portion 45 of the flange 44 and adapted to engage the walls thereof. 20 From the foregoing it is obvious that the arm 46 may be moved to contact with one or the other wall of the cut away portion 45 of flange 44 and accordingly the butterfly valve 40 is opened or closed thereby controlling 25 the passage of the exhaust gases through the casing 34 and into the foot lever 15.

The foot lever 15 particularly indicated in Figs. 7 to 10 comprises a body portion 30 51 substantially of rectangular cross section which decreases from the center toward the extremities. At each end the lever is provided with a slantingly directed chest or casing 52 of a contour to conform to the 35 toe portion of a shoe. The upper and lower walls of the casing are maintained at the same distance from one another throughout the dimensions of the lever 15. The upper side of the casing 52 is equipped with a 40 plate 53 of sheet metal or other suitable material or metal bent to form a pocket to receive the front portion of a shoe. At a distance from the upper wall of the casing 52 a foraminous plate 54 is provided secured 45 in any approved or convenient manner to the casing or plate 53 whereby direct contact between the shoe and the casing is avoided and in addition ventilation of the pocket is assured. As indicated in the drawings 50 a pocket is provided at each end of the lever which is supported to be oscillated in a horizontal plane, the movements of the lever being effected by means of the feet of the flyer. A partition 55 extends throughout 55 the entire lever and centrally thereof to divide the same into two compartments 57, 58, which are entirely separate except at the upper end of the casings 52, where the partition 55 stops short of the wall portion 56. The exhaust gases entering from the 60 valve 14 will thus divide and flow toward both extremities of the foot lever 15, in the compartment 57, thence between partition 55 and wall portion 56 into compartment 65 58. The two currents will meet at the egress

end 59 of the foot lever and flow through the pipe 16 into the succeeding control element. The lever 15 as indicated in Fig. 7 has at its extremities apertured lugs 60 for attachment of cables leading to the surfaces 70 of the aeroplane which are to be adjusted. The lever 15 is formed integral with, or has secured thereto, a downwardly extending sleeve 61 received within a standard 62 secured to the floor. A bolt 63 extends 75 through the sleeve and holds the latter to the standard thus acting as a pivot pin in the oscillatory movements of the lever. The construction of this standard and the various details of the lever are unimportant as far 80 as the general objects of the invention are concerned, and for this reason no further description of these parts is given, it being sufficient to point out that the passage of the gases remains undisturbed during the 85 movement of the lever except as for such restrictions imposed thereon by the adjustment of the valve 14. The foot lever as mentioned before is equipped with apertured lugs 64 at its ingress side to which the lugs 90 35 of the valve 14 are secured.

The control wheel 17 comprises a hollow rim 65 and a hub 66 interconnected with the rim by four spokes 67. As indicated in Figs. 14 and 15 two diametrically opposed spokes 67 are hollow and in communication with the rim. At the inner end the spokes are extended into the hub and terminate at stationary rings 68 and 69 respectively providing for the ingress and 95 egress of the exhaust gases. From the drawing it is apparent that the gases leaving the pipe 16 pass through the communicating spoke 67 into the hollow rim 65 where they divide and flow toward the other hollow spokes 67 thence to the ring 69 and into the pipe 19.

The modification shown in Fig. 3 is distinguished from the previously described arrangement by the provision of a control 110 lever 70 instead of the wheel control. The lever 70, as indicated in Figs. 4-6, is provided with a partition 71 stopping short of the upper end to establish communicating interior compartments 72, 73, through which 115 the gases pass. The base 74 of the lever comprises a tubular casing 75, provided with a rearwardly projecting extension 76 for the reception of the flexible pipe 19 leading to the hollow seat 20. The base is formed 120 at opposite sides with depending flanges 77, 78, which are apertured to receive a pivot pin 79. The flange 78 terminates in lateral flanges 80 apertured to receive pivot pins 81. As indicated in Fig. 6, a bearing 82 receives the pivot pins in slotted supports, so that the lever may be swung about the pins 81 in longitudinal direction with respect to the body of the aeroplane and in transverse direction about pin 79. A bottom plate 83 125 130

4

closes the lower end of compartments 72, 73. To the front side of the base a control valve 84 is secured, the casing of which forms a T and communicates with the compartment 72 of the lever 70. A butterfly valve 85 is secured to a spindle 86 extending through the casing and provided exteriorly with a handle 87 and a link 88 articulated with a connecting bar 89, which is pivotally connected with an arm 90 secured to a spindle 91 carrying a butterfly valve 92 and controlling the leg 94 of the casing 84. As will be obvious, the valves and links are so arranged that in the open position of valve 85 the valve 92 is closed and vice versa. A flexible pipe 93, secured to the leg 94, leads to a Y fitting 95 inserted in the flexible pipe 19 leading to the hollow seat. From the foregoing it is obvious that upon manipulation of handle 87 the valve 85 may be opened, whereby the gases flow in the direction indicated by the arrows in Fig. 6, or the valve 85 may be closed and the valve 92 opened, so that the gases flow through the by-pass 93, whereby the lever is disconnected from the heating system. In other respects this modification is similar to the one previously described and like parts are provided with like reference numerals.

30 The drawings indicate the employment of the exhaust gases for heating the controlling elements and the seat. Other appliances in the proximity of the pilot or observer, such as the map board and the like, can also be constructed to be amenable to internal heating.

It is our intention not to confine ourselves to the specific disclosures made in the application as to the kinds of elements heated and the mode of interconnecting the elements.

40 It is also within the scope of the invention to employ a source of heat other than the exhaust gases of the engine. Either an external or an internal source of heat may be used for heating the various controls of the machine or other devices in proximity to

the operators. Thus heat may be generated within the various elements by means of charcoal or other material, or hot gases may be conducted through the various devices which gases are obtained from any source other than the exhaust of the engine.

We therefore do not intend to limit ourselves to a particular heating medium, nor to movable controlling means, but we claim our invention as broadly as the state of the art permits.

We claim:

1. In an aeroplane, in combination with the combustion motor and the exhaust therefor, a plurality of hollow levers, means for conducting the exhaust gases through said levers, and a by-pass for disconnecting one of said levers from said conducting means.

2. In an aeroplane, in combination with a combustion engine and the exhaust therefor, a plurality of levers, means for conducting the exhaust gases through said levers, means for simultaneously controlling the passage of the exhaust gases through all of said levers, and means for independently controlling the passage through one of said levers.

3. In an aeroplane, in combination with the motor and the exhaust therefor, a plurality of hollow levers, means for conducting the exhaust gases through said levers, and means for controlling the passage of exhaust gases through one lever independently of the other levers.

4. In an aeroplane, in combination with the motor and the exhaust therefor, a hollow lever, means for conducting the exhaust gases through said lever, means for controlling the passage of the exhaust gases through said lever, and means for disconnecting the lever from said conducting means.

In testimony whereof we have herewith set our hands.

EDWARD BERNARD JAEGER.
EUGENE H. HELLER.
